UNITED STATES PATENT OFFICE.

H. CLAY BASCOM, OF TROY, NEW YORK.

DESIGN FOR A CANNON STOVE.

SPECIFICATION forming part of Design No. 16,423, dated December 22, 1885.

Application filed November 16, 1885. Serial No. 183,050. Term of patent 7 years.

To all whom it may concern:

Be it known that I, H. CLAY BASCOM, a citizen of the United States, residing in the city of Troy, in the county of Rensselaer and State 5 of New York, have invented and produced a new and original Design for Cannon Stoves, of which the following is a specification, reference being had to the accompanying engraving of a stove having said design.

10 This design embraces new and distinctive parts and combinations of parts, as hereinafter specified, and shown in the aforesaid engraving.

One part is the ornamentation of the door 15 A, consisting of the circular register a, the lower rosettes b, the leaves c, and the intermediate radial quadrant ornaments d.

Another part relates to the shape and ornamentation of the section B of the stove, the 20 same consisting of the projecting ring e, the upwardly-contracted and convexly-curved portion f, having along its upper part the serrated band f', the upwardly-tapering part g, the concave molding h, the fillet i, having a 25 series of semi rosettes, the convex molding j, and the top k.

Another part is the shape and ornamentation of the legs, consisting of the upper side parts, o, having the leaf ornaments p and 30 meeting at an angle, and the lower portion, q, having the compound flower and leaf ornament r.

The design for the stove-body consists of the

sections B and C, shaped and ornamented substantially as shown, the parts l, m, and n being 35 embraced by said latter section.

The whole design embraces the door A, sections B and C, and the legs, all shaped and ornamented so as to produce substantially the appearance represented in the accompanying 40 engraving.

I claim as new—

1. In a design for a stove, the ornamentation of the door A, consisting of the register a, rosettes b, leaves c, and ornament d, as 45 shown.

2. In a design for a stove, the shape and ornamentation of the section B, embracing the parts e, f, f', g, h, i, j, and k, as set forth.

3. In a design for a stove, the shape and 50 ornamentation of the legs, consisting of the parts o p and q r, as described and shown.

4. The design for the stove-body, consisting of the portions B and C, shaped and ornamented as set forth.

5. The whole design, embracing the door A, 55 sections B and C, and the legs, shaped and ornamented as set forth.

In testimony whereof I hereunto set my hand, in the presence of two subscribing witnesses, 60 this 13th day of November, 1885.

H. CLAY BASCOM.
